CLAIM

The ornamental design for a display screen or portion thereof with animated icon, as shown and described.

DESCRIPTION

FIG. 1 shows a display screen or portion thereof with animated icon showing a first image of our new design; and, FIG. 2 shows a second image thereof.

The appearance of the display screen or portion thereof with animated icon sequentially transitions between the images shown in FIGS. 1-2. The process or period in which one image transitions to another image forms no part of the claimed design.

The outermost dash-dot broken line in FIGS. 1-2 represents a display screen or portion thereof and forms no part of the claimed design. The short dash-long dash broken line in FIG. 2 illustrates a boundary of the claimed design and forms no part of the claimed design.
